UNITED STATES PATENT OFFICE.

SAMUEL H. GIBSON, OF CLEVELAND, OHIO, ASSIGNOR TO THE FANNER MANUFACTURING COMPANY, OF CLEVELAND, OHIO, A CORPORATION OF OHIO.

STIRRING DEVICE.

Application filed July 2, 1921. Serial No. 482,080.

To all whom it may concern:

Be it known that I, SAMUEL H. GIBSON, a citizen of the United States, residing at Cleveland, in the county of Cuyahoga and 5 State of Ohio, have invented a certain new and useful Improvement in Stirring Devices, of which the following is a full, clear, and exact description.

The present invention relates to a construction which is adapted for use in connection with a barrel or other similar container for the purpose of stirring and mixing the contents of the barrel.

In barrels or similar receptacles which are 15 used for the shipment of such materials as paint or analogous liquid materials which require stirring before they are dispensed from the barrel, it is practically speaking necessary to provide some form of stirring 20 device within the barrel in order to stir or mix the materials.

The present invention is directed to the provision of a stirring apparatus which may be inserted into the barrel after the barrel 25 has been completely manufactured with both heads in place without in any way dismantling the barrel. This is a feature which is very desirable inasmuch as the barrels are usually manufactured by barrel manufacturers complete, and subsequently sent to 30 other persons or places where the stirring devices are made and inserted in the barrel, and obviously if the barrel has to be dismantled in order to insert the stirring 35 device, it results not only in an increased labor cost for assembling the stirrer in the barrel, and additionally the barrels when partially dismantled and subsequently put together again are apt to be leaky.

Reference should be had to the accompanying drawings forming a part of this specification, in which Fig. 1 is an elevation with portions in section, of a barrel containing the stirrer of the present invention; 40 Fig. 2 is a side elevation with portions in section and illustrating the manner of insertion of the stirring device; Fig. 3 is a sectional elevation showing the lower bearing arrangement for the stirrer shaft; Fig. 45 Fig. 4 is a sectional elevation showing the lower bearing for the stirrer shaft in position; Fig. 5 is a view of the stirrer.

I indicates a barrel of conventional form, and while the term "barrel" is used in

this specification it should not be taken in 55 its restricted sense, but is inclusive of all forms of containers to which the invention is applicable.

The barrel is provided with oppositely disposed heads 2 and 3 which for the purpose of this specification I will denote 60 as the top and bottom, respectively.

The barrel is provided with the usual bung hole 4 which, when the barrel is filled with material, will be closed by any suitable means. The top of the barrel is provided with an opening 2^a which is located substantially in the center of the top, and the bottom is provided with an opening 3^a, 65 which is located substantially in the central 70 portion thereof.

The stirrer shaft is indicated at 5 and is of such a length that when the shaft 5 is properly positioned within a barrel, the top portion thereof will extend through the 75 opening 2^a. This will permit the engagement of the end of the shaft 5 by means of a suitable handle indicated at 6 so that the shaft 5 may be turned by the handle 6 to effect a stirring operation.

For the purpose of closing the hole or opening 2^a during shipment, there is provided a recessed cap member 7, which has a lower threaded portion that is screwed 80 into the opening 2^a. This cap member is of 85 such height that it lies below the chime of the barrel which is indicated at 8, and thereby in no way interfering with the barrel standing on either end.

The stirrer blade is indicated at 9 and 90 may be formed in any desired manner, one form which the stirrer may assume being shown in Fig. 5, wherein there are two oppositely extending blades 10 with an intermediate portion 11 having an opening there- 95 through and a set screw 12 which controls the said opening.

The lower end of the stirrer shaft 5 has a reduced or neck portion 5^a and a flange or head portion 5^b. This flange portion 5^b is of 100 substantially the same diameter as the diameter of the shaft 5.

The opening 3^a is adapted to receive a threaded plug or closure member 13 which is hollow. The lower exterior surface of 105 the plug 13 is screw threaded as indicated at 13^a and is adapted to be screwed into the opening 3^a.

The plug 13 adjacent the threaded end is provided with a small opening through which may be inserted a plug 14 that has a close fit in said opening. This plug will extend into the interior or hollow portion of the plug and is so inserted after the end of the shaft has been inserted within the plug 13 that the flanged portion 5^b of the shaft will lie below the plug 14.

10 In assembling the stirring device within a barrel, the shaft 5 is first inserted through the opening 2^a in a diagonal manner. The stirrer member 9 is inserted through the bung opening 4 and the end of the shaft 5 is inserted through the central opening in the stirrer member. The stirrer is secured onto the shaft 5 by tightening the set screw 12 and at a position on the shaft 5 above the reduced portion 5^a.

20 When this has been accomplished the stirrer blade is moved within the barrel and the end of the shaft 5 is inserted through the opening 3^a in substantially the position as shown in Fig. 3. The cap member 13 is then introduced over the end of the shaft 5 and the plug 14 is introduced which will prevent the outward movement of the shaft 5, or, in other words, prevent its disengagement from the cap 13. The cap 13 is then 30 screwed into the opening 3^a so that the shaft and cap occupy the respective relationship which is indicated in Fig. 4.

After this is done the cap 7 at the top of the barrel may be put in position and then 35 the barrel may be filled with the contents which it is to contain.

As before stated, when it is desired to mix or stir the contents of the barrel, the cap 7 is removed and the handle 6 introduced 40 upon the end of the shaft 5.

Having described my invention, I claim:—

1. The combination with a barrel or the like, having oppositely disposed heads and 45 an opening in each of said heads, a shaft extending through one of said openings, a stirring device on said shaft, a bearing cap occupying the other of said openings, such cap being hollow, the said shaft having an unthreaded flanged end portion which extends into said hollow cap, and means associated with the cap and with the shaft for retaining the flanged end of the shaft within the said cap.

55 2. The combination with a barrel or the like, having oppositely disposed heads and an opening in each of said heads, a shaft extending through one of said openings, a stirring device on said shaft, a bearing cap 60 occupying the other of said openings, such cap being hollow, the said shaft having a portion which extends into said hollow cap and being provided with an unthreaded flanged portion which lies within the cap, 65 a retaining member associated with the hol-

low cap adjacent the open end thereof for retaining the end of the shaft within the said cap.

3. The combination with a barrel or the like, having oppositely disposed heads and 70 an opening in each of said heads, a shaft extending through one of said openings, a stirring device on said shaft, a bearing cap, occupying the other of said openings, such cap being hollow, the said shaft having a reduced portion adjacent an end thereof and a flanged portion at the end thereof, said reduced portion of the shaft extending into the hollow cap, a pin extending from the cap into the said hollow portion thereof and 75 in position to retain the end of the shaft within the said cap.

4. The combination of a barrel or the like having oppositely disposed heads and an 85 opening in each of said heads, a shaft extending through one of said openings, a stirrer adjacent the opposite end of said shaft, the end of the shaft adjacent the stirrer being of such length that it may extend through the opening in one of the heads of the barrel, a cap member having a hollow interior which is insertable into the opening in the head of the barrel, the end of the said shaft having a flange, a pin member inserted through the said cap member, and extending 90 adjacent the shaft and above the flange thereon.

5. The combination with a completely assembled barrel or the like having a body portion and oppositely disposed heads, said body having a bung hole therein and one of said heads having an opening therein, of a shaft extending through the opening in the head, said shaft being movable angularly in said opening sufficiently to permit 105 the end thereof within the barrel to be swung to adjacent the bung hole, a stirring device of a size to permit its passage through said bung hole, said stirring device having means for securing it to said shaft, and a bearing cap carried by the opposite head adapted to receive the end of said shaft and provided with means for retaining the end of the shaft therein.

6. The combination with a completely assembled barrel or the like having a body portion and oppositely disposed heads, said body having a bung hole therein and one of said heads having a substantially central opening therein, of a shaft extending through 115 the opening, said shaft being of a size to permit of its being moved angularly in said opening sufficiently to permit the end thereof within the barrel to be moved to adjacent said bung hole, a stirring device of a size 120 to permit its insertion angularly through said bung hole, said stirring device having an aperture to receive said shaft and provided with means for securing said shaft in place 125 therein, and a bearing cap carried by the op- 130

posite head adapted to receive the end of said shaft and provided with means for retaining the end of the shaft therein.

7. The combination with a barrel or the like, having oppositely disposed heads and an opening in each of said heads, of a shaft extending into said openings, a stirring device secured to said shaft adjacent one of said heads, the end of said shaft adjacent 10 the stirring device extending through the head and having a flange outside the head

of the barrel, a bearing cap having a cylindrical recess adapted to receive said flanged end of said shaft, said cap having a retaining part adjacent its inner end which permits passage of said flanged end of the shaft into said cap by a movement of said cap prior to its insertion into said opening, and means for securing said cap in said opening.

In testimony whereof, I hereunto affix my 20 signature.

SAMUEL H. GIBSON.
